CLAIM

The ornamental design for a heat-conducting heat sink component for a three fluid heat exchanger, substantially as shown and described.

DESCRIPTION

FIG. 1 is an isometric view of the heat-conducting heat sink component for a three fluid heat exchanger, showing my new design;

FIG. 2 is an end view thereof, on an enlarged scale to which the opposite end view is substantially identical; FIG. 3 is a right side view (seen from the right side of FIG. 2) thereof on an enlarged scale;

FIG. 4 is a left side view thereof on an enlarged scale; FIG. 5 is a bottom view thereof on an enlarged scale; FIG. 6 is a top view thereof on an enlarged scale;

FIG. 7 is an isometric view of the heat-conducting heat sink component for a three fluid heat exchanger, showing my new design, but showing an alternative embodiment to that of FIG. 1;

FIG. 8 is an end view of the embodiment of FIG. 7 to which the opposite end view is substantially identical; FIG. 9 is a right side view (seen from the right side of FIG. 8) of the embodiment of FIG. 7;

FIG. 10 is a left side view of the embodiment of FIG. 7; FIG. 11 is a top view of the embodiment of FIG. 7, to which the bottom view is substantially identical.

FIG. 1

FIG. 2

FIG. 3

FIG. 4

FIG. 5

FIG. 6

FIG. 7

FIG. 8

FIG. 9

FIG. 10

FIG. 11
